UNITED STATES PATENT OFFICE.

FANNIE J. NILES, OF PHILADELPHIA, PENNSYLVANIA, ASSIGNOR TO THE NILES
NORMALIZING MACHINE CO., INC., OF NEW YORK, N. Y., A CORPORATION OF
NEW YORK.

MASSAGE-MACHINE.

1,291,611.

Specification of Letters Patent. Patented Jan. 14, 1919.

Application filed September 11, 1915. Serial No. 50,149.

To all whom it may concern:

Be it known that I, FANNIE J. NILES, a citizen of the United States, residing at Philadelphia, in the county of Philadelphia and State of Pennsylvania, have invented certain new and useful Improvements in Massage-Machines, of which the following is a specification.

My invention relates to improvements in massage machines, the object of the invention being to provide a massage machine which operates upon the patient while in a horizontal or inclining position, and imparts a soothing reciprocating rolling action upon any desired part of the body so as to reduce the flesh and operate as a remedy for many diseases or disorders due to obesity.

As excessive fat is evidence of two incorrect conditions, namely, lack of exercise and improper assimilation, people who are very stout are usually weak because much of the vital energy has gone to fat instead of muscular strength, and they require more energy to move than others, and it is difficult, if not quite impossible for fat people to use ordinary forms of exercise.

An apparatus embodying my improvements operates upon the body while the patient is lying down and no strain is upon the spinal column and without causing the patient any discomfort whatever.

A further object is to provide a machine of the character stated which can be readily adjusted for use with any size of body, and which may be used in connection with one or a plurality of massage devices and massage the portion or portions of the body desired.

A further object is to provide a machine of the character stated which can be manufactured and sold at a reasonably low price, and which will most efficiently perform the functions for which it is intended.

With these and other objects in view, the invention consists in certain novel features of construction and combinations and arrangements of parts as will be more fully hereinafter described and pointed out in the claims.

50 In the accompanying drawings:

Figure 1 is a plan view showing my improved machine equipped with two series of rollers constituting massaging devices.

Fig. 2 is a view in longitudinal section through the center of the machine showing a patient in position for operation.

Fig. 3 is a view in transverse section on the line 3—3 of Fig. 1.

Fig. 4 is an enlarged detail view illustrating one of the turn buttons, and

Fig. 5 is an enlarged fragmentary detail view partly in section and partly in elevation illustrating a portion of one series of rollers.

1 represents an operating table which is supported on hollow standards 2, and at one end is made with lateral extensions 3 at both sides as shown clearly in Fig. 1. These lateral extensions afford a wide rest for the arms during various positions of the body on the operating table.

A longitudinal shaft 4 is positioned centrally below the operating table 1, and is supported in bearings 5 in standards 2. On this shaft 4, a rectangular frame 6 is secured.

The frame 6 comprises parallel side bars 7, 7, connected by arms 8 with the shaft 4, and one of these arms 8 is connected by a link 9 with a crank pin 10 on a gear wheel 11, the latter secured to a short shaft 12 mounted in one of the standards.

The shaft 12 is connected by a gear train 13 with a motor shaft 14, the latter having a fly wheel 15 thereon, and operated by an electric motor 16 supported on a bracket 17 fixed to one of the standards 2 as shown clearly in Fig. 2.

The side bars 7 of frame 6 are provided throughout their length with turn buttons 29 which are adapted to connect a flexible massaging device herein shown to be in the form of series of rollers 18 to the frame 6 as will hereinafter appear.

In Figs. 1 and 2, I illustrate my improved machine provided with two series of rollers 18, but it is of course to be understood that the invention is not limited to any particular form of flexible massaging device nor to any number of series of rollers, nor to any particular location or arrangement, and the description hereinafter of one series of rollers will apply alike to both.

The rollers are each made of three sections 20, 21, and 22 respectively. The end sections 21 and 22 are relatively short, while

the intermediate sections 20 are relatively long, and all of these sections are provided with longitudinal bores for the reception of pins 23 upon which the rollers turn or which 5 turn with the rollers as desired.

Links 24 connect the pins 23, and are located between the sections of the rollers, and give to the series of rollers the necessary 10 flexibility to allow the same to conform to 10 the shape of the body.

The links 24 at the ends of the series of rollers are connected by pins 25 with flexible sheets 26 preferably of heavy canvas or other strong material having therein a plurality of eyelets 27.

It is to be understood that the eyelets 27 receive the turn buttons 29, and by providing several series of eyelets in the sheets 26 at the ends of each series of rollers, a wide 20 range of adjustment is permitted so as to give just the necessary pressure on the body, and to conform to the shape of the body.

The rollers 18 may, of course, be made of any suitable material, but I have found that 25 wood answers the purpose, and is preferably used, although I am not limited in this particular.

Fig. 2 illustrates a body 28 on the operating table 1, and across which two series of 30 rollers 18 are positioned, the ends of the series of rollers connected to the side bars 7 of frame 6.

Through the medium of the gears above described, motor 16 imparts a rotary movement 35 to gear 12, and crank pin 10 causes link 9 to impart an oscillating movement to the frame 6. This oscillating movement of the frame imparts a reciprocating movement to the series of rollers, and the latter 40 roll freely and smoothly over the body, backwardly and forwardly, imparting a correct massage movement and operating to reduce the flesh and cure ills as above explained.

45 While the body 28 is shown in one position, it is of course to be understood that the patient may be turned to any position desired, and the rollers operate upon any part of the body.

50 Various slight changes might be made in the general form and arrangement of parts described without departing from my invention, and hence I do not limit myself to the precise details set forth, but consider 55 myself at liberty to make such changes and alterations as fairly fall within the spirit and scope of the appended claims.

Having thus described my invention, what I claim as new and desire to secure by Letters Patent is:

60 1. In a massage machine, the combination with an operating table, of a flexible massaging device movable transversely of the table, and means for reciprocating the said 65 device, substantially as described.

2. In a massage machine, the combination with an operating table, of a flexible massaging device movable transversely of the table, and means below the table adapted to reciprocate the said device, substantially as 70 described.

3. In a massage machine, the combination with an operating table, of a massaging device movable transversely of the table above the same, an oscillating frame below the 75 table, and said massaging device connected to the frame, substantially as described.

4. In a massage machine, the combination with an operating table, of a massaging device movable transversely of the table above 80 the same, a horizontal oscillating frame below the table, and said massaging device having means at its ends whereby it is adjustably connected to the frame, substantially as described. 85

5. In a massage machine, the combination with an operating table, standards supporting the table in horizontal position, an oscillating frame supported in the standards below the table, and a massaging device connected to the frame and extending transversely over the table, substantially as described. 90

6. In a massage machine, the combination with an operating table, standards supporting the table in horizontal position, an oscillating frame supported in the standards below the table, a massaging device connected to the frame and extending transversely over the table, said frame having a series of turn 100 buttons at its side edges, and said massaging device having flexible perforated sheets at its ends to receive the turn buttons, substantially as described. 105

7. In a massage machine, the combination with a horizontal table, standards supporting the table, a shaft mounted to turn in the standards, a frame secured to the shaft, means for oscillating the frame, and a massaging device positioned transversely over 110 the table and connected at its ends to the frame, substantially as described.

8. In a massage machine, the combination with a horizontal table, standards supporting the table, a shaft mounted to turn in the 115 standards, a frame secured to the shaft, means supported by one of said standards for transmitting motion to the frame, and a plurality of massaging devices positioned transversely over the table and at their ends 120 adjustably connected to the sides of the frame, substantially as described.

9. A massage machine, comprising standards, a horizontal operating table supported on the standards, an oscillating frame supported by the standards below the table, a massaging device positioned transversely over the table and connected to the frame, a train of gearing supported by one of the standards, means connecting the train of 125 130 standards, means connecting the train of 130

gearing with the frame, whereby the latter is oscillated, and a motor for driving the gear train, substantially as described.

10. In an apparatus for massaging surfaces of a patient's body, the combination of a flexible massaging device movable in contact with the surface to be treated, means for supporting the patient in a reclining position engaged by said flexible massaging device and mechanism for moving said massaging device across the surface to be treated while the patient is reclining.

11. A massaging apparatus comprising a supporting table, a plurality of spaced apart massaging straps passing over said table, and adapted to engage different portions of a person resting on said table and means for moving said straps across said portions.

12. A massaging apparatus comprising a supporting table, a plurality of massaging straps passing over said table, means engaging the straps for moving the same back and forth over a portion of a person on the table, certain of said straps being relatively adjustable.

13. In a massage or body treatment machine, the combination with means for supporting the person to be treated in a horizontal position, of a series of elongated horizontally arranged massage devices, a flexible support for said devices, adapted to conform to the outline of the body of the person when in horizontal position, whereby a plurality of said massage devices will be brought into engagement with the upper portion of the body simultaneously, and means for moving said support to and fro to actuate said massage devices.

14. In a massage machine, the combination of two series of massage devices for engagement with the body of a person when in horizontal position, flexible carriers for carrying the massage devices of each of said series, means for adjusting said carriers to bring a plurality of the massage devices of each series into engagement with the body, and means for actuating said carriers.

15. In a massage machine, the combination with means for supporting a person in a substantially horizontal position, of a flexible massaging device movable transversely of the person, and means for reciprocating said device.

16. In a device of the class described, the combination of a table for supporting a body in a substantially horizontal position, a shaft positioned below the table, a rocking frame secured to the shaft, means carried by the frame for securing a body engaging member thereto, and means for rocking said frame.

17. In a massage apparatus, the combination of a table for supporting a body in a horizontal position, supports for said table, a shaft positioned below the table extending lengthwise thereof and carried by said supports, a rocking member carried by said shaft and extending laterally from opposite sides thereof, the outer ends of said member being provided with turn buttons thereby to connect opposite ends of a body engaging member thereto, a rotary power member carried by said supports and positioned below said rocking member and a link connection between said power member and said rocking member whereby the rotary movement of the power member is transformed into a rocking movement of said member.

18. In the art of treating a person's body, the method which consists in causing the patient to assume a horizontal resting position with the muscles relaxed and when so positioned to subject a portion of the surface of the body to the massaging action incidental to the reciprocating of a flexible massaging device back and forth across the surface supporting the device.

In testimony whereof I have signed my name to this specification in the presence of two subscribing witnesses.

FANNIE J. NILES.
